UNITED STATES PATENT OFFICE

150,940

DESIGN FOR A DESK LAMP OR THE LIKE

Herman L. Goebel, Chicago, Ill., assignor to Mitchell Manufacturing Company, Chicago, Ill.,
a corporation of Delaware

Application September 4, 1946, Serial No. 133,048

Term of patent 14 years

(Cl. D48—20)

To all whom it may concern:

Be it known that I, Herman L. Goebel, a citizen of the United States, residing at Chicago, in the county of Cook and State of Illinois, have invented a new, original, and ornamental Design for a Desk Lamp or the like, of which the following is a specification, reference being had to the accompanying drawing, forming part thereof.

Fig. 1 is a perspective view of a desk lamp or the like, showing my new design.

Fig. 2 is a side elevational view of same.

Fig. 3 is a front elevational view of same, and
Fig. 4 is a rear perspective view of same.

I claim:

The ornamental design for a desk lamp or the like, as shown.

HERMAN L. GOEBEL.
